UNITED STATES PATENT OFFICE.

EDWARD M. LANG, JR., OF PORTLAND, MAINE.

CLOSURE FOR CANS.

1,109,649.

Specification of Letters Patent.

Patented Sept. 1, 1914.

Application filed May 6, 1912. Serial No. 695,524.

To all whom it may concern:

Be it known that I, EDWARD M. LANG, Jr., of Portland, in the county of Cumberland and State of Maine, have invented 5 certain new and useful Improvements in Closures for Cans, of which the following is a specification.

My invention relates to the construction of cans such as are used in canning corn and other food products and it relates particularly to improved means for closing the stud hole or mouth of the can.

The invention is designed to remedy several difficulties which have hitherto been experienced in the canning industry.

My invention will be more readily understood by referring to the accompanying drawing wherein I have shown the old form of can closure and my improved forms.

In the drawing, Figure 1 is a vertical section showing the form of can closure now in common use, Fig. 2 is a like section showing my improved form, Fig. 3 shows my improved cap provided with a solder ring, Fig. 4 shows my improved cap formed to prevent close nesting, and Fig. 5 is a plan of the form shown in Fig. 4.

The difficulties in the canning industry referred to above are as follows: The common practice of forming the stud holes of the cans has been to form an annular downward depression around the stud hole, the inner and lower edge of this depression being turned upward at an angle, forming a plain edge over which the cap was fitted. This construction is shown in Fig. 1, in which *b* is the can top with the depressed portion *b'* and turned up edge *b*². The cap consisted essentially of a disk *a*, the outer edge *a'* of which was turned down to rest in the depressed groove or channel formed by the upturned edge *b*² of the stud hole opening. Two difficulties are found with this construction. In the first place the portion *b'* is depressed below the level of the can top in order to form the groove or channel to receive the edge *a'* of the cap. This depression which commonly drops about $\frac{1}{8}$ inch takes away just that much from the holding capacity of the can. The reason is that the liquid contents of the can cannot be allowed to come in contact with the can top for fear of "freezing" or chilling the soldering tool. There is also danger of the contents of the can being scorched

or burned by the heat of the soldering tool and this is particularly true of carbonaceous material like syrup or condensed milk. A space is thus commonly left between the 60 top of the material in the can and the under side of the head of the can and when the depressed groove encroaches on the interior of the can the level of the contents must be kept low enough to clear it. 65

One phase of my invention consists in so forming the cap and the stud hole as to avoid this depressed portion and to bring the soldering groove up to the general level of the can top, avoiding any encroachment 70 upon the available space within the can. Another difficulty with the old construction is that the inner edge of the stud hole is exposed after the can is sealed to the action of the contents of the can and as it is not 75 covered with the tin of the tin plate or the solder used in sealing the cap, it is liable to corrode and injure the contents of the can. I overcome this difficulty by so forming the joint that both the plain edge 80 of the cap and of the top are covered with solder.

Referring to Fig. 2, *e* represents the can top and *d* is the cap. The edge of the stud hole instead of being depressed as in the old form, is kept up above the level of the bottom of the can top by forming an inner annular groove *g* in the upper surface immediately adjacent to the edge *f* and an outer annular groove *h* on the under side 90 immediately adjacent to the groove *g*. The edge *f* thus projects upward and the groove *g* forms a channel to receive the downward projecting edge *i* of the cap. An annular groove *j* is formed on the under 95 side of the cap immediately adjacent to the outer edge *i* and in this groove rests the edge *f* of the stud hole. As here shown, I form an inner annular groove *j'* on the cap adjacent to the groove *j*, thus bringing the 100 body of the cap up to a level above that of the can top. The solder is applied with an annular soldering steel in the groove *g* in the usual way and the result of the soldering operation will be a ring *m* of solder in 105 the groove *g* and a ring of solder *k* which will accumulate in the groove *j* on the under side of the cap, working through the joint between the overlapping edges. The covering of the edge *f* of the top is caused 110 by the comparatively narrow groove *j* formed on the under side of the cap with

the edge f lying in and partially filling the groove. The capillary attraction draws the solder through the joint and holds enough in the V-shaped recess to completely cover the edge f when with the old construction the edge would be left uncovered as shown in Fig. 1.

- In the case of Fig. 1, if any solder comes through it will fall into the can since there is nothing to hold it on the under side. It will be seen that by forming the adjacent reverse grooves in the top surrounding the stud hole, the parts are raised above the level of the under side of the top so that the full capacity of the can may be utilized. A further advantage is that my construction tends to do away with the danger of scorching and burning the contents of the can where such substances as syrup and other carbonaceous material are canned. By raising the level of the soldering groove it is kept well away from the contents of the can. It is evident that the system of grooving the top for the purpose of raising it may be used with the old form of cap and that the cap formed to produce a double ring of solder to cover both plain edges may be used in connection with the old form of stud hole. Hitherto when it has been desired to provide the caps with a solder ring before applying them, the solder has been applied to the cap in the form of a flat ribbon which was crimped over the edge of the cap. A cap formed as shown in Fig. 2 with a distinct groove on the under side adjacent to the outer edge enables me to compress a ring of solder in the bottom of such groove, this being a much simpler operation than "hemming" the cap.
- In Fig. 3 I show one of my caps n with its outer edge q and an adjacent groove p and a ring r of solder pressed, molded or otherwise introduced into the groove. The ring may be continuous or it may be otherwise distributed in the grooves, the essential thing being to provide solder enough to form the joint perfectly. Caps of this form are liable to rest so closely that it is sometimes difficult to separate them. This is particularly so when they are automatically

fed in a cap dropping machine or a cap hemming machine. To avoid this I may form this groove in segments, leaving between the segments one or more of the partitions which are a continuation of the body of the cap. In Figs. 4 and 5 I show such a construction in which s is the body of the cap, t the groove, and u partitions separating the grooves into three sections. When the caps are piled in a column one on another, there will be a separation of the edges because the grooves will not nest perfectly on account of the presence of the partitions. Thus the separating blade or other device which may be used will easily find its way between the caps.

It will be seen that by the use of my invention I am enabled to utilize the entire depth of the can, covering the plain edge of the stud hole with solder so that no corrosion will take place.

It is evident that while I have herein shown my invention as applied to a can having a relatively small stud hole or opening, it may equally well be applied to what is called an "open topped can" in which the cap or closure occupies substantially the entire top of the can. The groove h instead of being a relatively narrow groove may be as wide as desired and may if desired extend out to the edge of the can.

I claim;—

A can cap adapted to form with other like caps, columns with relatively open joints or spaces said cap consisting of a metal disk having an outer annular groove formed on its under side immediately adjacent to its outer edge and an inner annular groove on the upper side adjacent to the outer groove, said inner groove being divided into sections by one or more small plain portions in the same plane as the upper surface, to prevent the caps from closely nesting.

In testimony whereof I have affixed my signature, in presence of two witnesses.

EDWARD M. LANG, JR.
